UNITED STATES PATENT OFFICE.

CHARLES A. BORCHERT AND MICHAEL G. O'NEIL, OF WOODLAWN, PENNSYLVANIA.

VALVE.

1,267,365.

Specification of Letters Patent. Patented May 28, 1918.

Application filed December 13, 1917. Serial No. 208,841.

To all whom it may concern:

Be it known that we, CHARLES A. BORCHERT and MICHAEL G. O'NEIL, both residing at Woodlawn, in the county of Beaver and State of Pennsylvania, citizens of the United States, have invented or discovered certain new and useful Improvements in Valves, of which improvements the following is a specification.

10 The object of our invention is to provide a valve which may be operated in high pressure steam, water or other fluid conducting lines without liability of cutting the co-operating seating portions of the valve closing members, or otherwise rendering the valve incapable of preventing leakage when closed.

In the accompanying sheet of drawings, which forms part of our specification, we 20 have illustrated the preferred embodiment of our invention. Figure 1 is a longitudinal central sectional view of the valve in closed position; Fig. 2 a detached sectional view of the co-operating valve members showing them in valve-cracking or closing positions; and Fig. 3 a view similar to Fig. 2 showing the valve members in open position.

The valve casing may be of any desired form suitable to the particular service in 30 which the valve is intended to be used. In the illustrative embodiment of our invention we have shown a globe valve casing 1 provided with an inlet 2 and outlet 3, and a partition 4 provided with a port 5 affording 35 communication between the inlet and outlet.

While we have designated particular openings of the casing as inlet and outlet openings and have indicated by arrows the flow through the casing as entering the inlet and 40 discharging through the outlet, it will be understood that the flow may be in the opposite direction, as more fully explained hereinafter.

Our invention has particularly to do with 45 the means for controlling flow through the valve port 5 or a similar port in any other specific type of valve casing. The means which we provide for this purpose comprise a pair of specifically shaped co-operating 50 members which may be designated as a seat-provided sleeve member 6 and a valve closure member 7, which members are movable with relation to each other to open and close the valve. While either member may be movable, we prefer to move the closure 7. Accordingly the sleeve 6 may be attached to

the partition 4 and projects from a side thereof as indicated in the drawings, and the closure 7 may be attached to a longitudinally movable stem 8 of any well known or desired construction.

The sleeve 6, which may be of any desired cross-sectional shape but which is preferably cylindrical, is provided interiorly at its outer end with a valve seat 9. This seat, being 65 within the sleeve, necessarily lies below the outer end thereof; and, while it may be variously shaped, it is preferably formed by beveling the interior of the sleeve as indicated in the drawing. 70

The valve closure 7 is provided with a seating portion 10 adapted to co-operate with the sleeve seat 9 to prevent flow through the sleeve. The closure is also provided with a flange 11, which telescopes in close-fitting 75 contact with the exterior of the sleeve 6 and projects beyond (downwardly, as viewed in Fig. 1) the seating portion 10 of the closure. In the drawings the flange 11 is shown as extending to the plane indicated at 12. For 80 the purpose of guiding the valve closure 7 to its closed position, the flange 12 may be provided with an extension 13 in which there are formed ports 14.

In describing the operation of the valve 85 it will be assumed first that the valve is closed and that the flow, when the valve is opened, is in the direction of the arrows shown in Fig. 1. As soon as the closure 7 is raised a slight distance from the sleeve 90 6 there will be a slight leakage of fluid between the co-operating seating portions, but actual practice has shown that this slight leakage does not cut such seating portions. In fact this leakage is beneficial when the 95 valve is being closed, the leakage being effective to remove from the seating portions of the valve members any foreign matter that may have lodged thereon. The cracked portion of the valve is indicated in Fig. 100 2, and it will be observed that the jet of fluid between the lower end 12 of the flange 11 and the upper edge of the sleeve 6 will not impinge upon either the closure seat 10 or the sleeve seat 9, the former being above 105 the lower end of the flange and the latter below the top of the sleeve. Thus there can be no cutting of these seating portions while the valve is being cracked, and it is well understood that the cutting of the 110 valve seating portions of valves as they are usually constructed takes place while the

valve is being cracked or while it is being closed.

When the flow of fluid through the valve is in the opposite direction from that indicated in Fig. 1, there can also be no cutting of the seating portions. When the valve is thus used, it will be observed from Fig. 2 that because of the wide separation of the seating portions of the valve when in cracked position, the jetting of the fluid will take place entirely between the lower end 12 of the flange 11 and the upper end of the sleeve 6, and that the only cutting action will be upon the lower edge of the flange. It will be understood that such cutting of the flange as may thus take place will in no way impair the effectiveness of the valve to prevent leakage when closed.

According to the provisions of the patent statute we have described the principle and operation of our invention together with the valve construction which we now consider to represent the best embodiment thereof. However, we desire to have it understood that our invention may be practised with other forms of construction than that specifically shown and described.

We claim as our invention:

1. The combination with a valve casing provided with an inlet and an outlet and with a port affording communication therebetween, of means for controlling flow through said port, said means comprising a sleeve member provided interiorly with a valve seat and a closure member adapted to

fit said seat, said closure being provided with a flange telescoping in close-fitting contact with the exterior of said sleeve and projecting beyond the seating portion of said closure, and means for moving one of said members with relation to the other.

2. The combination with a valve casing provided with an inlet and an outlet and with a port affording communication therebetween, of a sleeve projecting from a side of said port and provided interiorly with a valve seat, and a movable closure adapted to fit said seat and provided with a flange telescoping in close fitting contact with the exterior of said sleeve, said flange projecting beyond the seating portion of said closure.

3. The combination with a valve casing provided with an inlet and an outlet and with a port affording communication therebetween, of a sleeve projecting from a side of said port and beveled interiorly at its outer end to form a valve seat, and a movable closure beveled to fit said seat and provided with a flange telescoping in close-fitting contact with the exterior of said sleeve, said flange projecting beyond the seating portion of said closure.

In testimony whereof we have hereunto set our hands.

CHARLES A. BORCHERT.
MICHAEL G. O'NEIL.
